US00D869859S

(12) **United States Design Patent** (10) Patent No.: **US D869,859 S**
Treeby et al. (45) Date of Patent: **** Dec. 17, 2019**

(54) **HAIR BRUSH**

(71) Applicant: **TANGLE TEEZER LIMITED**,
London (GB)

(72) Inventors: **Cameron Bruce William Treeby**,
London (GB); **Julian Leslie Meagher**,
London (GB)

(73) Assignee: **Tangle Teezer Limited**, London (GB)

(**) Term: **15 Years**

(21) Appl. No.: **29/668,519**

(22) Filed: **Oct. 31, 2018**

Related U.S. Application Data

(63) Continuation of application No. 35/502,947, filed on Nov. 7, 2016 (U.S. filing date under 35 U.S.C. 384), and having an international filing date of Nov. 7, 2016, now abandoned.

(74) *Attorney, Agent, or Firm* — Tarolli, Sundheim, Covell & Tummino LLP; John A. Yirga, Esq.

(57) **CLAIM**

The ornamental design for a hair brush, as shown and described.

DESCRIPTION

FIG. 1 is a top plan view of a hair brush in accordance with our ornamental design;

FIG. 2 is a bottom plan view thereof;

FIG. 3 is a front elevation view thereof;

FIG. 4 is a left side elevation view thereof;

FIG. 5 is a front perspective view thereof;

FIG. 6 is a rear elevation view thereof;

FIG. 7 is a rear perspective view thereof; and,

FIG. 8 is a right side elevation view thereof.

Those portions of the Figures shown in broken lines are included for environmental purposes only and form no part of the claimed design.

1 Claim, 8 Drawing Sheets
